UNITED STATES PATENT OFFICE.

ALFRED J. SHIPLEY, OF WATERBURY, CONNECTICUT, ASSIGNOR TO THE SCOVILL MANUFACTURING COMPANY, OF SAME PLACE.

DESIGN FOR A TROUSERS FASTENING-BAR.

SPECIFICATION forming part of Design No. 30,233, dated February 21, 1899.

Application filed January 13, 1899. Serial No. 702,102. Term of patent 14 years.

To all whom it may concern:

Be it known that I, ALFRED J. SHIPLEY, a citizen of the United States, residing at Waterbury, in the county of New Haven and 5 State of Connecticut, have invented and produced a new and original Design for Trouser Fastening-Bars, of which the following is a full, clear, and exact description.

This invention relates to that form of garment-clasps known in the trade as "trousers" hooks and bars, the same being made in pairs and each pair comprising a hook and a bar.

The present invention consists of a design for the bar of a trousers hook and bar.

15 In the accompanying drawings, forming part of this specification, and in the two figures of which like parts are similarly designated, Figure 1 is a perspective view of the bar, and Fig. 2 is a half-section and elevation thereof.

As shown in the drawings, the leading or material feature of my design consists of the rounded hollow protuberances a, arranged at opposite ends of the bar b; and my design as a whole comprises a bar for a trousers hook 25 and bar having the protuberances arranged substantially as shown and described.

Having described my invention, what I claim as new, and desire to secure by Letters Patent, is—

The design for a trousers fastening-bar, substantially as herein shown and described.

In testimony whereof I have hereunto set my hand this 11th day of January, A. D. 1899.

ALFRED J. SHIPLEY.
